Application January 20, 1954, Serial No. 405,173

5 Claims. (Cl. 242—9)

The present invention relates to winding apparatus and more particularly to an apparatus for winding potentiometers which are automatically compensated for a prescribed load impedance.

An object of this invention is to provide an improved winding apparatus.

Another object of this invention is to provide an improved winding apparatus for winding potentiometers and the like.

Another object of the present invention is to furnish an improved winding apparatus for producing a potentiometer having a non-linear resistance characteristic.

Still another object of the invention is to supply an improved winding apparatus for winding potentiometers which are automatically compensated for a particular load impedance to which the potentiometer is adapted to be connected.

Another object of this invention is the provision of apparatus for winding a resistance element in the form of a series of elastic sub-portions on a form in a manner to provide a potentiometer whose output precisely follows a prescribed function when connected to a particular load impedance.

A still further object of the invention is to provide a potentiometer winding apparatus for winding a resistance element in the form of a series of turns on a winding form wherein control means is furnished for automatically determining the rate at which the turns are to be wound, said rate being a function of the load to which the potentiometer is adapted to be connected.

Another object of the invention is to provide improved winding apparatus for producing a potentiometer from a reference potential source which follows a prescribed function, the resistance of said potentiometer following a second function at variance with said predetermined function but the potential output from said potentiometer following said predetermined function when connected to a predetermined load impedance.

Other objects of the invention will be pointed out in the following description and claims and illustrated in the accompanying drawings, which disclose, by way of examples, the principle of the invention and the best mode, which has been contemplated, of supplying that principle.

In the drawings:

Fig. 1 is an electromechanical schematic diagram of the winding apparatus;

Fig. 2 is an electrical schematic diagram of the winding apparatus;

Fig. 3 is a schematic diagram of a typical servoamplifier which may be used with the winding apparatus;

Fig. 4 shows an enlarged section of a number of the turns making up the resistance element and the contact means for engaging the coils;

Fig. 5 is an elevation of the potentiometer in a finished state;

Fig. 6 is a view taken on line 6—6 of Fig. 5, parts of the view being broken away for greater detail; and

Fig. 7 compares the characteristic curve of the master

with the characteristic curves of various potentiometers compensated for different load impedances.

Similar reference characters represent similar parts throughout the several views.

5 The manufacture of high precision potentiometers such as those used in modern analog computers is extremely difficult, particularly where the tolerances are quite small. These potentiometers are usually of the multiple-turn helical type and often have an over-all linearity requirement of less than .02 percent error.

At present, one method of manufacturing precision potentiometers is to accurately wind the resistance wire on a mandrel in the amount desired. The spacing of the wire on the mandrel may be accomplished through lathe feedings means. The mandrel is then wound around the potentiometer core to form a helical coil. A wiper arm may then ride in a groove adjacent the coil and pick off various levels of potential between the two ends of the coil.

Difficulties arise in this particular method due to differences in the wire diameter, the coil diameter, the coil spacing, and the non-uniformity of resistance of the wire itself.

These difficulties were overcome in a manner described in patent application Serial No. 357,165, filed May 25, 1953, for Method and Apparatus for Winding Potentiometers and Article Produced Thereby, by Curt I. Johnson. In the aforementioned patent application it was proposed to wind the resistance wire in the manner of a spring. By winding a spring of suitable resistance material with 30 a spring index of approximately six, and with sufficient initial tension so that the spring is closely wound, the spacing of each coil is directly proportional to the mean diameter of the spring and inversely proportional to the wire diameter. Therefore, the resistivity of the wound spring is a function of similar relationships.

The spring is formed by winding the wire on a mandrel into coils closely adjacent each other. The angle of feed of the wire to the mandrel is adjusted so that it forms an acute angle with respect to the portion of the spring already wound. Thus, an initial tension can be placed in the spring. The mandrel is removed and the spring is ready for use as the potentiometer resistance element.

By placing the length of spring having a desired overall resistance on a suitable bobbin, a potentiometer of single or multiple turns can be wound on a winding form from the bobbin. The bobbin and the form to be wound are both driven and means is provided to vary the speed of the bobbin to permit a uniform resistance element to be wound on the form. This is accomplished by providing a master potentiometer having a pick-off means, the arrangement being such that as said pick-off means moves from one end of the resistance element to the other, the variation in resistance is directly proportional, within certain tolerances, to the amount of movement. Pick-off means is also provided closely adjacent the point of application of said spring resistance element to said winding form. A potential is applied across said spring resistance element and said master potentiometer and said master potentiometer and said winding form are driven in synchronism. The potentials at the pick-offs associated with said winding form and said master potentiometer are compared and the difference therebetween is used to vary the rate of rotation of the bobbin. Thus, the resistance of the resistance element on the winding form follows the same characteristic function as the reference potential.

With the above-described method and apparatus it is possible to wind a potentiometer, the resistance of which may be characteristically linear or non-linear, depending upon the resistance of the master potentiometer. In other words, the potentiometer produced is a precise copy of the master potentiometer.

A difficulty arises, however, in the use of this type of potentiometer. It will be seen, that if a load impedance is placed across the output terminals of the potentiometer, the potential at said terminals will not follow the same characteristic curve, as the pick-off moves from one end of the resistance element to the other, as that followed by the resistance. As the value of impedance changes the variation of the potential from said linear curve also varies. As the load impedance goes down, the variation from linearity goes up, and vice versa.

To overcome the last-named difficulty it is proposed to actually wind the spring resistance element on the winding form such that the resistance, from one end to the other, does not follow the same characteristic curve as the potential from the master potentiometer. An impedance, such as a resistor, is placed between the pick-off means associated with the winding form and some point on the spring resistance element, and the resistance element is then wound on the form. When a load impedance, the equivalent of the aforementioned impedance, is connected to the pick-off and said one end, and the pick-off is moved from one end of the resistance element to the other, the voltage obtained follows the same characteristic curve as that followed by the resistance of said master potentiometer. In other words, if the resistance on said master potentiometer, from one end to the other, follows a linear characteristic curve, the output potential from the winding form, from one end to the other, will also follow a linear characteristic curve.

For a more detailed description of the invention reference is made to Fig. 1, which is an electromechanical schematic diagram of the winding apparatus, and Fig. 2, which is an electrical schematic of the circuitry involved. In the drawings, electrical wires are indicated by solid lines and mechanical shaft connections are indicated by dotted lines. After the resistance wire has been wound on the mandrel so that the turns or coils are in contact with each other the mandrel is removed. Sufficient initial tension is used in the initial winding to assure accurate coil spacing. The length of coils appears as a helical spring.

It will be understood that while I have referred to the resistance element as being in the form of a series of turns or coils, the sub-portions could take other forms. It is but necessary that they be of a form which permits elasticity or expansion, the term expansion being used hereinafter to mean either increase in length or decrease in length. Stated another way, the resistance element is of a construction such that the resistance per unit length may be varied.

For a more detailed description of the manner of winding the resistance wire on the mandrel, reference is made to application Serial No. 165,623, filed June 2, 1950, for Spring Coiling Device by Curt I. Johnson and James A. Nord, now Patent No. 2,650,638, issued September 1, 1953.

A length of straight wire is placed adjacent the length of coils. One end of the resistance element and one end of the straight wire are secured to one end of the storage bobbin. The straight wire is then made taut and the resistance element is expanded to separate adjacent coils thereof along the length of the straight wire. When sufficient spacing is provided so as to prevent shorting between the coils the coils are wound on the bobbin.

The storage bobbin includes a cylindrical surface which is provided with a helical groove extending the length thereof. The resistance element is adapted to fit within the groove. The storage bobbin is shown schematically in Fig. 1 at 10. The end of the resistance element fixed to the bobbin is electrically connected to slip ring 11 associated with the bobbin. The other end of the resistance element is connected to one end of the potentiometer form or core illustrated by the reference numeral 12, the details of which are shown in Figs. 5 and 6. The slip ring 13 is electrically connected to the last-named end of the resistance element. A D. C. potential is applied across the entire spring by connecting to slip rings 11 and 13.

Once the spring resistance element is connected to the potentiometer core the straight wire may be removed from the bobbin.

A reference voltage potential is obtained by providing 5 a master potentiometer illustrated by numeral 14. This master potentiometer is preferably a potentiometer with the best possible degree of precision. It will be understood that other means could be provided as long as a precision source of voltage is furnished to which the 10 potentiometer being wound can be compared.

A drive motor 15 is excited by 115 volt 400 C. P. S. A. C. power supply and is shaft connected through gear 16 to a slip ring 17 associated with potentiometer 14. As schematically shown, slip ring 17 is secured to 15 an arm 18 which is adapted to move around the periphery of the potentiometer. A contact supporting member 19 is slidably mounted on arm 18 and is adapted to follow a helical groove adjacent the helical resistance winding of the potentiometer. A contact 20 is mounted on member 19 and is adapted to ride on the potentiometer resistance element. The ends of this last-recited resistance element are connected to a D. C. power supply so that 20 a potential is placed thereacross.

Slip ring 17 is shaft connected to slip ring 13 and 25 core 12. Both slip rings are connected to one side of a gear differential 21. Another side of the differential is shaft connected to slip ring 11 and bobbin 10. A motor generator servo unit 22 is shaft connected to the 30 third side of the differential and is adapted to vary the drive speed of the bobbin with respect to the core 12 in accordance with the rate at which the spring must be wound on the core to reproduce the master potentiometer. That is, the length of the spring can be varied in order 35 to control the spacing of the coils which are wound on the core.

In order to control the motor generator servo unit 22 a contact 23 is mounted on a contact supporting member 24, said member 24 being slidably mounted on a 40 fixed arm 25 adjacent core 12. A guide groove is provided adjacent the helical groove of the core for receiving a finger 26, shown in detail in Figs. 5 and 6, said finger being secured to member 24. As the core is rotated, finger 26 rides in the guide groove and causes member 24 to move along arm 25. In this manner contact 23 engages the spring resistance element adjacent 45 its point of application to the core. The spacing of the contact means with respect to the point at which the resistance element is applied to the core may be varied to provide optimum correction for error in the distribution of the resistance in the resistance element before it is fixed on the core. The length between the point of engagement by the contact means and the point where the element is fixed in relation to the core becomes the working length where the distribution is accurately controlled.

An impedance, such as resistor 90, is connected between the pick-off output terminal and the terminal of the resistance element which is connected to the low side of the input potential. It should be made clear 60 that the impedance could just as well be connected between the pick-off output terminal and the terminal of the resistance element connected to the high side of the input potential. It is but necessary that the impedance be connected to the same terminals which will later be used as output terminals to connect to the load impedance.

Reference is now made to Fig. 2 along with Fig. 1. The spring resistance element being wound on core 12 is illustrated by numeral 27. The D. C. power supply 70 places the same potential across resistance elements 14 and 27. Contact 20, which picks off a potential from potentiometer 14, is connected to ground potential. Terminal 28 of chopper 29 is also grounded. Arm 23 picks off a potential from resistance element 27 and 75 supplies this potential to terminal 30 of the aforementioned chopper.

Chopper 29 further includes an arm 31, said arm being pivoted at one end and adapted to contact terminals 28 or 30 at the other end thereof. A series connected coil 32 and capacitor 33 are connected to an A. C. power supply of 115 v. 400 C. P. S. Therefore, arm 31 is moved into contact alternately with terminals 28 and 30 at the rate of 400 cycles per second.

In view of the above it will be seen that an output signal will be produced as long as there is a potential difference between terminals 28 and 30. This output signal is RC coupled by resistor 34 and capacitor 35 to transformer 36, the output of which is applied across a resistor 37. An output signal is picked off the resistor at a desired level and fed to a first amplifier 38 where the signal is amplified. The amplifier output signal is fed to a phase adjusting network 39 from which it is fed to servoamplifier 40.

Amplifier 40 may be in the form of a conventional servoamplifier of a number of stages sufficient to obtain proper amplification. While the details of the amplifier do not form a part of the invention a schematic circuit of an amplifier which may be used is shown in Fig. 3. Briefly, the amplifier includes a voltage amplifying input stage 41, the output of which feeds across a transient bypass capacitor 42 and is RC coupled to the control grid of a second voltage amplifying stage 43. The output voltage from stage 43 is fed to a phase shifting network 44 which advances the phase of the signal 90°. The output signal from network 44 is supplied to one side of a duo-triode 45, the output of which is supplied through a voltage divider network 46 to the other side of the duo-triode. Thus, tube 45 acts as a push-pull amplifier stage. The output signals from tube 45 are 180° out of phase and are RC coupled to a second duo-triode 47 which acts as a push-pull power stage of amplification. From the plates of tube 47 the output is limited by diode 58 and coupled through transformer 48 to the control winding 49 of motor 50, said motor being a portion of servo unit 22. Motor 50 is shaft connected to the generator portion 51 of said unit. Both the motor and generator are of the two-phase type. A reference potential of 26 v. 400 C. P. S. A. C. is applied to the fixed windings 52 and 53 from the system power supply. The output winding 54 of the generator feeds back to the amplifier degeneratively for damping purposes. As shown in Fig. 3, the generator output feeds to the control grid of tube 43 through a resistor 55. The phase difference between the feedback voltage from the generator and the input voltage supplied from amplifier 41 is 180°.

The shaft output from servo unit 22 is connected to differential 21, as shown in Fig. 1, so as to control the rate of rotation of storage bobbin 19.

The overall mode of operation of the present invention will now be described. A D. C. potential is applied across the master potentiometer 14 and the resistance element 27 which is being wound on the core 12 from storage bobbin 10. A drive motor 15 is connected to drive the master potentiometer 14 and the core 12. Motor 15 drives storage bobbin 10 through differential 21. As the resistance element is being wound on the core a comparison is made between the potentials at contacts 20 and 23 to provide a signal which is a function of the error in the distribution of the resistance of the resistance element which is about to be wound on the form. If there is no error between the potentials no output signal is fed through the chopper and amplifiers to servo unit 22. The shaft connecting the servo unit to the differential is stationary and therefore storage bobbin 10 and core 12 are rotated at the same speed. However, if there is an error, which in the present invention appears as a potential difference between contacts 20 and 23, the difference potential exists between terminals 28 and 30. It will be seen that terminal 28 is placed at ground potential. If terminal 30 is above ground potential the out-

put voltage from the chopper will be of one phase and if terminal 30 is below ground potential the output voltage from the chopper will be of the opposite phase. The phase of the output signal determines the direction of 5 rotation of the shaft output from servo unit 22 and the amplitude of the output signal determines the rate of shaft rotation. Therefore, if too much of the resistance element 27 has been traversed by the pick-off at a particular instant the shaft output from the servo unit, 10 through the differential, decreases the rate of rotation of bobbin 10. If not enough of the resistance element 27 has been traversed by said pick-off the servo unit shaft output is in the opposite direction and increases the rate of rotation of bobbin 10. The increase or decrease in 15 the rate of rotation of bobbin 10 increases or decreases, respectively, the resistance of the resistance element per unit length. As the resistance per unit length changes the coil spacing is also changed. Therefore, the distribution of the resistance of the resistance element which is applied 20 to the core is accurately controlled by the error signal.

Reference to Fig. 7 will clearly reveal the relationship between the resistance characteristic of a particular reference and the resistance characteristic of a plurality of potentiometers wound according to the instant invention, 25 each of said plurality of potentiometers being compensated for different load impedances. In this instance the particular reference source has a linear resistance characteristic but it will be understood that this has been chosen only by way of example. The resistance curve for the 30 reference is illustrated by numeral *a*. Curves *b* and *c* represent the resistance characteristics for first and second potentiometers, respectively, which have been compensated for different load impedances. The load impedance corrected for by the aforementioned first potentiometer 35 is higher than corrected for by the second potentiometer. It is seen that the lower the load impedance the greater the variation from the reference.

When the load impedance for which the potentiometer 40 is compensated is coupled to the proper output terminals, the voltage output from the potentiometer will follow the same characteristic curve as the resistance of the reference follows.

With the instant invention, variations of the output 45 potential from a desired characteristic curve due to load impedance are effectively compensated for. When a customer desires a potentiometer for a particular use, it is but necessary for him to specify the function which the output voltage is to follow, the load impedance which is to be connected to the output terminals, and which end 50 of the potentiometer is to be used as one of the output terminals. The present apparatus is used to wind a potentiometer, the resistance of which does not follow the desired function, but when the output terminals are connected in accordance with the customer's specifications the output potential does follow said desired function.

It will be obvious to those skilled in the art that the 55 resistor 90 does not have to be connected to one particular end of the resistance element. It could in fact be connected between any point on the resistance element and the pick-off in accordance with a customer's specifications. For example, the impedance could be connected between a center tap on the resistance element and the pick-off in order to provide a particular potential output.

Fig. 4 shows in a somewhat exaggerated manner the space relationship between coils constructed from wire of varying diameter. For example, the wire of coils 60, 61 and 62 is smaller in diameter than the wire of coils 63, 64 and 65. It will be noted, however, that the spacing between coils 60, 61 and 62 is greater than that 60 between coils 63, 64 and 65. The resistance of the individual coils decreases with increase in wire diameter and the variable spacing compensates therefor. It should be further pointed out, by way of example, that where it 70 is desired that the output potentials from the potenti- 75

ometer follow a linear characteristic curve when connected to a particular load impedance, the spacing of the coils will also vary in accordance with the degree of variation of the resistance from linearity.

In order that the correct spacing of the coils is always maintained provision is made for securing the coils to the winding form. One way which has shown good results is to mix an epoxy resin into a liquid state and applying a thin film thereof to the helical groove into which the resistance element is to be placed. This is allowed to air dry until it becomes tacky. This occurs toward the end of the "pot life" of the resin, and the winding operation is then performed. After the element is completely wound on the core, the complete unit is placed into an oven of 60°-80° C. and slowly rotated. The resin becomes soft and then hardens to a solid state. The hardened substance covers the lower portion of the coil to impart additional rigidity thereto.

After the core has been completely wound it may then be assembled with the remainder of the potentiometer. The complete assembly is shown in Figs. 5 and 6. The winding form or core 12 is fixedly mounted on the base plate 66. The mechanical connection of the ends of the resistance element 27 is illustrated by numerals 67 and 68, said connections being at opposite ends of the core and spaced 180° apart. The electrical connections for the potentiometer are spaced 90° from the mechanical connections. As shown, a small wire 69 is led from a connection at one end of the effective resistance via a longitudinally extending slot 70 to a terminal post 71. A heavier wire 72 is connected to the terminal post for connection to one side of the power supply which may be either an A. C. or D. C. source. A small wire 73 connects the other end of the effective resistance and the terminal post 74. A heavier wire 75 connects to the last-named post and extends through a longitudinally extending aperture 76 to the other side of the aforementioned power supply.

The contact supporting arm 77 is connected to one end of a member 79, said last-named member being secured centrally thereof to a shaft 80. Shaft 80 extends through core 12 and base plate 66 and is journaled therein. A second arm 78 is connected to the other end of member 79 and is adapted to counterbalance arm 77. The contact 23 and its supporting member 24 are similar to those shown in Fig. 1 and are illustrated by similar reference numerals. The finger 26 is adapted to ride in the helical groove 81.

The electrical pick-off is through contact 23, supporting member 24, arm 77 and member 79 to a slip ring 82. Slip ring 82 is secured to shaft 80 along with member 79. A pair of wire contacts 83 are mounted on a terminal plate 84 and are adapted to engage slip ring 82 for picking off the electrical potential thereon. A wire lead 85 is connected to terminal plate 84 and fed through aperture 76 to the other end of the core. A slot 86 is provided in base plate 66 to permit leads 72, 75 and 85 to be led from the potentiometer.

From the above it will be seen that a potential is applied to the coils between the connection of wires 71 and 73. Rotation of arm 77 permits contact 23 to pick off any potential between the points of applied potential.

The above-detailed description relates to a preferred embodiment of the invention. It will be understood, however, that various elements are shown which serve only by way of example as a means for carrying out the invention. The master potentiometer could be replaced by any kind of voltage supply which would supply a potential with which the potentiometer being wound is to bear a relationship. For example, it will be seen that a switchable decade box could be used. A source of potential could be applied across a resistor or a series of resistors, there being relay controlled means programmed to switch in and out small increments of resistance to provide a very accurate reference potential. While a D. C. error detect-

ing network has been shown and described in the preferred embodiment, an A. C. error detecting network could be provided. The amount of initial tension which is placed in the spring resistance element may be increased or decreased in accordance with the requirements of the situation. While a chopper has been shown as a means for obtaining a usable output signal from the voltage difference between the potentiometer pick-off, it will be seen that other means could be provided without departing from the scope of the invention. It is but necessary that a signal be obtained which is a measure of the error of one with respect to the other. It should be further understood that potentiometers other than linear potentiometers may be manufactured with the present apparatus. By providing a particular non-linear potentiometer or other voltage source as a reference the servomotor control will regulate the rate of feed of the resistance spring to the core. The only limitation comes in the amount the individual coils can be spaced. That is, they cannot be so close together as to provide a short circuit or so far apart as to prevent engagement between at least one of the coils and the contact means. Too great a spacing results in an open circuit.

While there have been shown and described and pointed out the fundamental novel features of the invention as applied to a preferred embodiment, it will be understood that various omissions and substitutions and changes in the form and details of the device illustrated and in its operation may be made by those skilled in the art, without departing from the spirit of the invention. It is the intention, therefore, to be limited only as indicated by the scope of the following claims.

What is claimed is:

1. In an apparatus for producing potentiometers, a resistance element whose resistance per unit length may be varied, contact means for traversing the length of a portion of said resistance element, means for making substantially all of the part of said portion traversed by said contact means rigid so that the distribution of the resistance of said rigid part may not be varied, means for applying a potential across said portion, impedance means connected to said contact means and to a fixed point on said rigid part, a source of reference potential which varies according to a prescribed function, means for detecting the error between the potential at said contact means and said reference potential and providing a signal which is a function thereof, and means responsive to said signal for controlling the distribution of the resistance of said portion which has not become rigid.
2. In an apparatus for producing potentiometers, a resistance element in the form of a series of elastic sub-portions, said resistance element having a potential applied across a portion thereof, contact means, means mounting said contact means for traversing along the length of said portion from one end of said portion to the other, means for applying a part of said portion which has been traversed by said contact means to a form so that the distribution of the resistance of said part is substantially fixed, impedance means connected between a fixed point on said portion and said contact means, a source of variable reference potential, means for providing a signal which is a function of the error between the voltage at said contact means and said reference potential, and means responsive to said signal for determining the distribution of said elastic sub-portions before they are fixed to said form.
3. In an apparatus for winding potentiometers, a resistance element, said resistance element being in the form of a series of turns the spacing of which may be varied, contact means, means mounting said contact means for movement over said turns from one end of said resistance element to the other, means for mounting a portion of said resistance element traversed by said contact means on a form in a manner to make substantially all of the turns of said portion in fixed spaced

relation, impedance means connected between a point near one end of said resistance element and said contact means so that it is in parallel with the portion of said resistance element between the last-named one end and said contact means, a reference potential which varies in accordance with a function, means for comparing the potential at said contact means with said reference potential and providing a signal which is a function of the difference therebetween, and control means responsive to said signal for determining the spacing of the turns of said resistance element as they are applied to said form.

4. An apparatus for winding potentiometers which are adapted to be connected to a predetermined load impedance and whose voltage output when connected to said load impedance will follow a predetermined function, comprising a resistance element whose length may be varied, contact means mounted for movement along a portion of said resistance element from one end of said portion to the other, means for supplying a potential across said portion, means for applying a substantial part of said portion traversed by said contact means to a form so that the distribution of the resistance of said part is substantially fixed, impedance means, said impedance means being substantially equivalent in value to said load impedance and connected to the same points of said portion to which the load impedance is adapted to be connected, a source of reference potential which follows said predetermined function, means for comparing the potential at said contact means with said reference potential and providing a signal which is a function of the error therebetween, and means responsive to said signal for determining the distribution of the resistance of said portion before it becomes fixed to said form.

5. An apparatus for winding potentiometers which are adapted to be connected to a predetermined load impedance and whose voltage output when connected to said load impedance will follow a predetermined function, comprising a resistance element having a plurality of sub-portions which are of the same general configuration, contact means mounted for movement along a length of said resistance element from one end of said length to the other, means for supplying a potential across said length, means for applying a substantial part of said length traversed by said contact means to a form so that the sub-portions thereof bear a fixed relation to each other, impedance means, said impedance means being substantially equivalent in value to said load impedance and connected to the same points of said length to which the load impedance is adapted to be connected, a source of reference potential which varies according to a predetermined function, means for comparing the potential at said contact means with said reference potential and providing a signal proportional to the error therebetween, and means responsive to said signal for controlling the rate at which the sub-portions are applied to said form.
